UNITED STATES PATENT OFFICE.

FRANK E. BURLEY, OF CHICAGO, ILLINOIS.

DESIGN FOR A GRAPE-FRUIT HOLDER.

No. 37,905.

Specification for Design.

Patented March 20, 1906.

Application filed March 13, 1905. Serial No. 249,961. Term of patent 14 years.

To all whom it may concern:

Be it known that I, FRANK E. BURLEY, a citizen of the United States, residing at Chicago, in the county of Cook and State of Illinois, have invented a new, original, and ornamental Design for Grape-Fruit Holders, of which the following is a specification, reference being had to the accompanying drawing, forming a part thereof.

The figure is a perspective view of a grape-fruit holder, showing my new design.

I claim—

The ornamental design for a grape-fruit holder, as shown.

FRANK E. BURLEY.
